(57) **CLAIM**

The ornamental design for a stand and lavatory, as shown and described.

DESCRIPTION

In a preferred embodiment, the nature of this product is as a pedestal primarily useful for supporting and including a plumbing fixture such as a lavatory.

FIG. 1 is a left, top, front perspective view of a stand and lavatory embodying my new design;

FIG. 2 is a top plan view thereof;

FIG. 3 is a front elevational view thereof;

FIG. 4 is a left side elevational view thereof, the right side elevational view being a mirror image of the left side shown; and,

FIG. 5 is a rear elevational view thereof.

The broken line representations of mounting holes in FIGS. 1-2, and of a plumbing nipple in FIGS. 3-5, are for the purpose of illustration only, and form no part of the claimed design.
